CONTROL DEVICE FOR STEAM LOCOMOTIVES

François Marie André Athanase Walckenaer,
Paris, France; vested in the Alien Property Cus-
todian

Application September 7, 1939, Serial No. 293,848
In France November 19, 1938

13 Claims. (Cl. 60—102)

The present invention relates to a system providing, in a simple and convenient manner and from a central control station, complete control of the operation of a plurality of steam turbines driving a plurality of independent axles of a prime movement such as a locomotive.

The operation of such a prime movement and in particular of a locomotive with independent axles, each axle of which is actuated by a separate turbine presents, from the point of view of starting and control in the course of operation, a large number of comparatively difficult problems.

It is first necessary to provide at starting for progressive heating of the turbines and the simultaneous starting of a complete system of lubrication of the different mechanisms to be placed in motion, and also provide for circulation of oil under pressure for the control of the various regulating and safety devices.

It is then necessary to pass from this preparatory condition to the normal operating conditions.

During normal operation it is necessary to be able to shift from forward running to backward running, and vice versa; to regulate both in forward running and in backward running the effort applied to the several axles; to control as closely as possible the power supplied at a given moment by each of the turbines; and to provide an automatic safety device coming into operation when the speed of one or more of the axles exceeds the set amount and also adapted to be directly operated from the central control point if, for any reason, this is judged necessary.

The general system and combination which forms the object of the present invention and which will be described hereafter with reference to the annexed drawings, by way of example, permits of attaining this result.

On the said drawings,

Figure 1 represents a general diagram of the arrangement of the control system forming the object of the invention.

Figure 2 represents a diametrical section of the central steam supply and safety valve, of its control piston, of the distributor which regulates its movements and of the reaction valve which, through the intermediation of the pressure gauge located at the central control station, indicates the position of the valve.

Figure 3 represents a vertical section on the line III—III of Figures 4, 5, 6 and 7 of the valve chest through which the central control hand-wheel arranged at the central control point en- 55

sures the passing from forward running to backward running, and vice versa, and furthermore ensures, for each direction of running, the regulation of the efforts applied to the axles of the locomotive.

Figures 4, 5, 6 and 7 represent four vertical sections (the two last being partial sections) made respectively on the lines IV—IV, V—V, VI—VI and VII—VII of Figure 3.

Figure 8 represents a plan view of the portion of the valve chest which is located below a plane VIII—VIII of Figure 3.

Figure 9 represents a section on its vertical symmetrical plane of one of the valve distribution devices, for forward and backward running, with which each of the motor groups is provided.

Figure 10 represents a section on its symmetrical plane of one of the different regulator relays with regulation of rate of running and with subdivided piston, utilised for the control of the admission valve both in forward running and in backward running, two relays of this kind being provided for each of the turbines, one for the forward and one for backward running.

Figure 11 shows a detail section on the line XI—XI of Figure 10, and showing the regulating device for the rate of running by means of which it is possible to equalise almost completely between themselves the rates of operation of the 30 different relays of the different motor groups which are allotted to the same direction of running.

Figure 12 represents a section on its symmetrical plane of one of the oil pumps which are mounted at the end of the shaft of each of the turbines.

Figure 13 represents a section on its symmetrical plane of the expansion valve permitting of obtaining the circulation of oil under pressure practically constant, which is necessary for the operation of the valve chest, as also for the control of the regulator relays, of the central steam supply and safety valve, and of its group of disengaging relays.

Figures 14 and 15 represent respectively sections on their symmetrical planes, the first of the central ejector supplying the lubricating piping, and the supply of the pumps or generators of pressure of the group of disengaging relays of the safety valve, and the second of the ejector taking up oil from the casings.

Figure 16 represents a collection of sections (made on their symmetrical planes) of the different apparatus which combine to embody the central safety system, that is: the central group

of disengaging relays associated with the different motor groups, the pumps with which the said motor groups are provided and the control mechanism which permits of acting directly if desired from the central station, at the position of the central group of disengaging relays in question.

As will be seen from the following description, the whole organization of the system which forms the subject of the invention is based on the provision of a principal circulation main for oil under high pressure, the piping 1, which is adapted to be supplied in two ways, that is to say, on the one hand, at the moment of starting or during slow running, by an auxiliary pump 2 arranged in the oil reservoir 3, and on the other hand in full running, by the different pumps 4 which are mounted at the shaft ends of the different turbines (Fig. 12).

This principal oil circulation main has first of all to supply the ejector 5 which is fitted in the oil reservoir 3, and which, through the intermediation of the auxiliary piping 6, ensures the general lubrication of the machine and through the piping 7, connected to the preceding one, supplies the impellers or pressure generators 8 as also the group of safety and disengaging relays 9 (Fig. 16) at the same time as it supplies the pumps 4 through the piping 10 (Fig. 12).

This same trunk main has furthermore to supply the ejector 11 which, with a view to returning it to the reservoir 3 through the piping 12, ensures the taking up of the oil which has collected at the lowest point of the system of casings.

Finally, the said principal trunk main has to supply the pressure reducing valve 13 (Fig. 13) which itself has to supply with oil at reduced pressure but as constant as possible the secondary circulation network 14, which by its different ramifications, supplies the valve control chest 15, the relays 16, 17 of each turbine, the distributor or slide valve 18 of the steam supply and safety valve 19 as also its checking device 20 (Fig. 2) and its group of disengaging relays 9 (Fig. 16).

The piping 21 which passes to the control pressure gauge 22 fitted in the central control station A, starts from the checking device 20.

On the other hand, an auxiliary circuit constituted by the pipings 23 and 24 is arranged between the group of disengaging relays 9 and the common return pipe 25, passing through the central starting and safety control 26 also fitted at the central station A.

Finally, there are installed in the latter the central control handwheel 27 which through the intermediation of the valve chest 15, controls the operation of the different relays and of the cock 28 which for starting permits, through the intermediation of the automatic cock 29, of allowing the pump 2 to come into operation, this ceasing automatically to operate as soon as the speed of the machine has attained a sufficiently high value for the pressure of oil supplied by the centrifugal pumps 4 and delivered into the piping 1 to cause the closing of the cock 29. To this end cock 28 is provided with a pipe 28a supplying automatic cock 29 with steam taken from the locomotive boiler adjacent the superheater.

The automatic cock 29 may comprise any suitable valve device which is moved to open or closed position depending on whether the oil pressure in the piping 1 is below or above the

desired value. Preferably a piston or diaphragm-operated valve is used in which the flow of oil to the piston or diaphragm is controlled by a spring-loaded pressure-responsive pilot valve such as disclosed, for example, in Fig. 1 of U. S. Patent No. 1,968,656 (the adjustable setting of the spring to accomplish speed regulation being unnecessary).

In the general arrangement forming the object of the invention, the obtaining and harmonizing of the different conditions or periods of operation which must be considered, are obtained owing to the combination for the heating and supply with steam of the different turbines, of the common supply and safety valve 19 already mentioned and which will be described in detail hereinafter with reference to Figure 2, with individual groups of valves, that is, one per turbine, of which one will also be described hereinafter with reference to Figure 10.

The said linkage is based on the fact that the valve 19 is constructed and is controlled in such manner as to be able to ensure separately and according to the existing conditions, two distinct rates of output, one of small and constant amount for the period of heating the turbines, and the other, on the contrary, variable, regulated by the individual groups of valves and of quantity as great as is necessary for the full supply of the turbines at their maximum rate of running, the same valve being able when safety demands it, to arrest the complete supply.

To this end, as shown in Fig. 2, the valve 19 at which the piping 30 terminates which brings it the steam coming from the super-heaters of the source of steam which is a suitable boiler and from which starts the piping 31 which serves the different individual groups of valves of the different turbines and to which are connected the pipes 31a, 31b, and 31c, comprises a principal hollow valve 32 in which there is fitted at the extremity of a pilot piston 33, an auxiliary valve 34, the internal cavity 35 of the principal valve 32 communicating with the supply steam chamber 36 by one or more orifices 37 of comparatively small dimensions, made in the upper wall of the said principal valve 32.

The pilot piston 33, which carries the closing portion 34 of the auxiliary valve and which can undergo a certain longitudinal displacement in the recess 39 allotted thereto in the interior of the cap 40 of the principal valve 32, is mounted on a rod 41 with which it is integral and this rod 41, the upper part 42 of which is movable in a suitable guide 43 made in the upper cover 44 of the valve casing, is extended downward through the lower chamber 45 of the said casing, through a stuffing box 46 by the intermediation of which it passes out of the latter and so into the interior of a control cylinder 47 in which moves a piston 48 with which the lower extremity 49 of the rod 41 is connected immovably.

Between the upper end 50 of the cylinder 47 and the upper face of the piston 48, there is arranged a spring 51 tending constantly to move downward the piston 48, the rod 41 and consequently the two valves 34 and 32, the second being brought down by the first.

In the lower cover 52 of the cylinder 47, is arranged the distributor by means of which the control oil comes underneath the piston 48 and also by means of which the said oil is evacuated when the piston descends again and when consequently the valve closes.

To this end, the distributor in question com-

prises on the one hand, a piston 53 movable in the interior of a sleeve 54 and subjected to the action of a spring 55 tending constantly to thrust it towards the right, and on the other hand, a certain number of suitably arranged orifices.

One of these orifices, the orifice 56, is arranged between the right-hand extremity of the chamber in which the piston 53 moves, and the piping 57 by which the oil under pressure arrives, which comes from the pipe 14 from the pressure reducing valve 13 after having traversed a suitable throttling device 58.

There is branched on to the pipe 57 between the orifice 56 and the throttle 58, a pipe 59 which passes to the safety relay 8 and the role of which will be explained hereinafter.

A second orifice 60 and a third orifice 61 permit, according to the position of the piston 53, either that the oil coming through the pipe 57 and the orifice 56 penetrates below the piston 48 or that the oil which is under the said piston escapes through the drain pipe 62.

The lower face 63 of the piston 48 is profiled in such manner that on penetrating into a suitable cavity of the lower cover 52 of the cylinder 47, it acts as a dash-pot. A pipe 64 allows the oil to flow which is under the rod 41.

Finally, with the valve properly so called, and with its control rod 41 there is associated an indicator device constituted by a lever 65 hinged at 66 on to a fixed point and connected on the one hand at one of its extremities to a collar 67 integral with the rod 41 and on the other hand at its other extremity to the upper end of an auxiliary rod 68 which passes into a lateral cylinder 69 inside which are arranged, first of all a retaining washer 70 integral with the rod 68, and secondly a valve 71 adapted to slide with respect to the said rod and nevertheless guided with respect thereto, seeing that this latter penetrates into a cavity 72 suitably made to this end, a spring 73 being compressed between the upper washer 70 and the valve 71.

At its lower part the cylinder 69 is connected on the one hand through a pipe 74 to a pipe 14 distributing expanded fluid, but with the interposing of a throttling device 75, and on the other hand through pipe 21 to the pressure gauge 22 of the central control station.

In its central part, the said cylinder 69 communicates through a conduit 78 with the upper chamber of the cylinder 47 and at its upper part it comprises oil escape conduits 78a and 78b.

The operation of the device is as follows:

When it is desired to start the locomotive and in order to proceed to the preliminary heating of the turbines, a commencement is made by acting on the cock 28 of the central control station so as to start the auxiliary pump 2. This latter then delivers oil into the piping 1 under a sufficient pressure to ensure a satisfactory circulation of lubricant and to supply the pressure reducing valve 13, as also the different control apparatus.

When the pressure supplied by the pressure reducing valve 13 in the piping 14 attains the necessary minimum value, the action of this pressure on the piston 53 of slide valve 18 causes the displacement of the latter from the right towards the left in spite of the opposing effort of 70 the spring 55, the extremity of the pipe 59 which terminates at the safety relay 8 being naturally supposed to be closed at this moment and this can be made sure of by manipulating in the suitable direction as will be explained hereinafter, 75

the control mechanism 28 of the central station.

As soon as the piston 53 shifts from the right towards the left, the orifice 60 is uncovered allowing the oil to pass underneath the piston 48 and, in spite of the opposing action of the spring 51, commences to thrust it upward, so causing the opening of the auxiliary valve 34.

The steam which comes through the pipe 30 into the space 36 can then pass to the pipe 31 through the orifices 37 and through the auxiliary valve 36.

The precaution having been taken, by a suitable manipulation of the handwheel 27 which will be pointed out hereinafter, of maintaining fully open the valves of the different groups of valves of the turbines, the small quantity of steam which passes through the valve 36 easily flows through the turbines without having any other effect thereon except an exchange of heat. 20 Simultaneously, the pressure exerted on the small valve 71 by the spring 73 partially compressed in consequence of the movement of the lever 65 has been increased causing the oil pressure in pipe 74 to increase due to the increased resistance 25 encountered by the oil flowing between the valve and its seat. This pressure is indicated on the pressure gauge 22 opposite a mark H for "heating."

When, afterwards, it is thought that the turbines 30 are sufficiently heated, and to place the locomotive in a condition for starting, it is only necessary according to what will also be explained hereinafter, to effect the closing of the individual groups of valves of the turbines.

35 Since from this moment the steam which passes through the valve 36 finds no outlet towards the exterior, the principal valve 32 which the pressure of oil was not capable of opening before its balancing, is now rapidly balanced and the pressure of the oil which passes through the pipe 57, continuing to make itself felt under the piston 48, the valve 32 can then fully open; simultaneously the pressure exerted on the small indicator valve 71 by the spring 73, completely compressed owing to the displacement of the lever 65, shows on the pressure gauge 22 opposite a mark O for "opening."

The locomotive now being ready, the effective starting, either in the forward direction or backward, and the regulation of the speed for one or the other of the two directions of running under consideration, is obtained by manipulating the handwheel 27, by means of the different devices represented on Figures 3 to 11.

As will be seen on these figures and in particular in Figure 8, the handwheel 27 controls directly or at a distance a shaft 79 arranged in the casing of the valve chest 15, and on which are keyed in suitable positions one with respect to the other, four cams 80, 81, 82, 83 of which two, for example the cams 80 and 81, are allocated to running forward and the two others, the cams 82 and 83 are allocated to the backward running.

These four cams which follow the shaft 79 in its movements of rotation are movable with respect to four rollers respectively 84, 85, 86 and 87, mounted at the extremities of four gear levers 88, 89, 90 and 91 hinged at four fixed points 92, 93, 94 and 95 and connected at their opposite extremities to four rods 96, 97, 98 and 99.

The operation being the same for the two groups, this operation will only be described for a single group.

At the lower part of the casing of the valve chest 15, there is a space 100, which communi-

cates through an orifice 101 and a pipe 101a with the constant pressure pipe 14 of medium value coming from the pressure reducing valve 13.

At the upper part of the said space 100 there are arranged two valves respectively 102 and 103 mounted at the lower extremities of the rods 87 and 88.

There are, on the other hand, arranged on these same rods, a little above the valves, pistons 104 and 105 and, when the valves are open and 10 when the oil coming through the orifice 101 flows in below them, the upward differentials of the pressure on the upper and lower faces of the valves and on the lower faces of the pistons tend to constantly apply the rollers 85 and 86 on 15 their respective cams 81 and 82, in the manner of a resetting spring. The oil after having passed through the valves 102 and 103 runs, according to circumstances, through the orifice 107 or through the orifice 108 into the chambers 109 or 20 110 which are located opposite two other valves 111 and 112 which are arranged at the lower extremity of the rods 86 and 89 with the possible sliding of the said valves with respect to the rods and the interposition of springs 113 and 114, the 25 upper extremities of which are stopped against supporting washers 115 and 116 firmly attached to the rods 86 and 89.

Between the chambers 109 and 110 and the valves 111 and 112, there are arranged respectively 30 throttling devices 117 and 118 which, in combination with the said valves, regulate the pressure of the oil which is conveyed through the orifice 119 and the piping 119a to the different servomotor relays 16 for forward running.

From the cavity 110, the pressure of the oil is transmitted through the orifice 120 and the piping 120a to the different servomotor relays 17 for backward running.

But in each case it is only necessary to apply 40 the pressure to the said relays; actually it flows between the valves 111 and 112 and their seats (one or the other according to circumstances) and the residual pressure which it undergoes and which it applies to the relays is a function of the resistance which the springs 113 and 114 oppose to the opening of the valves 111 and 112.

This resistance is itself a function of the position produced by the handwheel 27 on the cams 45 or 88.

Altogether the general operation is as follows:

The four cams 80, 81, 82 and 83 are of such a shape and are arranged in such a manner with respect to one another that for the position of stoppage or dead point, the two valves 102 and 103 are closed and the compression applied to the two springs 113 and 114 is the minimum.

On the contrary, as soon as the handwheel is turned for example in the direction corresponding to forward running, the cam 81 (the slope of which is extremely rapid and the remainder of the profile of which is circular) immediately causes the complete opening of the valve 102; the oil under pressure coming through the pipe 101a then flows into the cavity 109 and under the valve 111.

As at this moment the cam 80 is at the commencement of its progressive travel, the compression given to the spring 113 is comparatively small and the pressure transmitted to the relays 16 is not very great.

It will be seen later on how the application of this pressure causes the opening of the steam supply valves allocated to forward running.

The excess oil which escapes between the valve 75

111 and its seat is discharged through the orifice 121 and the pipe 121a.

If the handwheel 27 is continued in its rotation in the same direction, the position of the valve 102 remains unchanged and the latter continues fully open, but the pressure exerted by the lever 88 on the spring 113 is greater, the oil has greater difficulty in passing between the valve 111 and its seat, its pressure increases, and it consequently applies a greater pressure to the relays. It will be seen that this increase of pressure has, as a consequence, a larger opening of the valves of the turbines.

During this period the valve 103 which corresponds to backward running remains closed.

When, afterwards, the handwheel is turned in the opposite direction, first of all the opening of the valve is reduced and then the dead point or point of stoppage is reached for which the valve 102 is completely closed, and the movement continuing in the same direction the valve 103 is suddenly opened and a certain pressure is delivered to the relays 17 controlling the backward running.

In each case the opening of the supply valves is caused and regulated as follows:

There is associated with each turbine a group of valves according to that which is shown on Figure 9.

In accordance with what is shown on this figure, each group comprises, mounted in a box 122, on the one hand, the group of forward running valves, for example three, 123, 124 and 125, and on the other hand, the valve or valves 126 for backward running.

In the embodiment represented, the three valves for forward running are mounted on a common cross-piece 127 in such manner as to be able to open or close successively, their respective rods being of different lengths.

The entirety of the valves for forward running is controlled by the rod 128.

The backward running valve is controlled independently by the rod 129.

45 The backward running valve 126 shown on the drawing, is an equilibrium valve with double seat comprising for its lower valve 130 an elastic connection device constituted by an elastic washer 131 the outer edge of which is integral with the valve 130 and the centre of which is bolted onto the lower extremity 132 of the rod 129.

The control of each of the rods 128 and 129 of each of the groups of valves of each turbine is ensured by a particular servomotor relay 16 of the type which is shown in Figures 10 and 11.

All the motor relays for forward running communicate with the piping 119a coming from the valve chest 15 (Fig. 3).

All the backward running relays communicate with the piping 120a coming from the valve chest 15.

As will be seen in Figure 10, the control rod of the valves, for example, the rod 128 is attached at 133 to a lever 134 which is hinged at 135 to 65 a fixed support 136 and of which the extremity 137 is subjected to the action of a return spring 138, whilst its other extremity 139 is connected by a hinged connecting rod 140 to the upper extremity of the rod 141 of the central sliding element 142 of the divided piston 143 of the servomotor 144, the operation of which is regulated, through the intermedium of the conduits 145 and 146 by means of the distributor 147.

The latter is constituted by a piston valve 148 subjected to the action of a traction spring 149

the upper extremity of which, ensuring the necessary control reaction, is integral with a piston 150 fixed to a rod 151 connected by a lever 152 and by a connecting rod 153 to the lever 134, the lever 152 being itself hinged through a link 154 to a fixed pivot 155.

The operating oil arrives through the conduit 156 and leaves through the conduit or pipe 157.

In accordance with what is shown in Figure 11, a regulating screw 158 allows the position of the pivotal point 159 of the lever 152 to be varied and consequently permits of varying, in a direct ratio, the effect of reaction resulting from the ratio of the two arms of the said lever with respect to its pivotal point.

The result is that the direct ratios of deformation of the different springs of the different relays, the actions of which should remain continuously identical, being capable of presenting certain differences among themselves, the said regulating screw permits, by its action, of ensuring the indispensable equality between the said direct ratios of variation, the initial regulation being effected by means of the length of the spring.

The operation of the device is as follows:

When a certain variation, for instance an increase, is produced in the pressure of the oil in the piping 119a and in the space 160, the slide valve 148 lowers slightly; it thus places the piping 146 in communication with the discharge piping 157 and it also places the delivery pipe 156 for the actuating oil in communication with the conduit 145. Owing to this, the piston 142, 143 sinks, carrying with it the lever 134 and causing a displacement of the valves 123, 124 and 125 in the opening direction.

But simultaneously the lever 134 acts on the connecting rod 153, on the lever 152 and on the rod 151 in such manner as to raise the piston 150, this latter in carrying with it the spring 149 moves upward the piston valve 148 and this latter again closes the communication between the conduit 156 and the conduit 145 as also the communication between the conduit 157 and the conduit 146. The piston 142, 143 is stabilised until there occurs a fresh variation in the pressure of the oil contained in the pipe 119a and in the space 160.

If this variation is in the direction of a reduction, the operation of the members is the reverse in this sense that the piston valve 148 commences by rising, placing on the one hand the actuating oil conduit 156 in communication with the conduit 146, and on the other hand the conduit 145 in communication with the exhaust conduit 157, and the piston 142, 143 rises; but at the same time as it causes a movement of the valve in the sense of closing, it causes by reaction a falling of the piston 150 and the return of the piston valve 148 to its mean position of equilibrium and of the closing of the distribution.

The divided character of the piston 142, 143 prevents the steam admission valves from being applied too suddenly on their seats, and the rod system from undergoing excess fatigue. When the pistons 142 and 143 move upwardly by reason of the oil under pressure entering through passage 146, its annular part 143 is brought to rest by shoulder 145a of cylinder 16 before the valves are completely seated. The oil then flows under pilot piston 142 and moves the latter upwardly which completes the seating of the valves. The operation in the opposite direction is obvious.

From the moment when the turbines are running, the oil which should supply the princi-

pal trunk main 1 distributing the oil under pressure is supplied by centrifugal pumps 4, the rotors or discs 161 of which are mounted at the extremity 162 of the turbine shafts (Fig. 12).

These rotors are supplied with oil through the branch 10 of the collector 6 supplying the principal ejector 5; they force it through the check valves 163 and pipe 1a into the conduit 1 under a pressure which is a function of the square of the speed of rotation of the turbine shafts.

When the pressure of this oil reaches a value slightly greater than that of the oil delivered by the pump 2, the latter stops automatically, the admission valve 29 for the steam which sets it in operation itself closing automatically.

If later on the speed of the locomotive is sufficiently reduced for the pressure of the oil delivered by the pumps of the turbine shaft ends to be insufficient, the pump 2 comes again automatically into operation through the automatic opening of the cock 29.

There is seen at 164 the lubrication conduit for the shaft bearing, which is fed from the lower branch of trunk 6.

In Figure 13 there is shown the oil pressure reducing valve 13 of known type, which is interposed between the principal main one for the circulation of oil at high pressure varying with the speed of the turbine, and the distribution piping 14 of oil at low and approximately constant pressure.

The oil arrives through the conduit 165 and leaves after reduction of its pressure by the conduit 166. The reduction of pressure and the delivery are regulated by a valve 161, the control rod 168 of which is integral with a piston 169 provided with a tight joint 170 and sliding in a cylinder 171 inside which is enclosed a spring 172, the pressure of which balances that exerted on the piston 170 by the oil flowing past valve 161.

The principal ejector 5 represented on the Figure 14, comprises as usual a diffuser 173 the mouthpiece 174 of which is arranged in the interior of the oil reservoir 175 opposite the tuyère 176.

The collector ejector 11 shown on Figure 15 also comprises a diffuser 177 the mouthpiece 178 of which is arranged in the vicinity of the bottom point of the casings, opposite the nozzle 179.

The safety system with which the device forming the object of the invention is provided is constituted in combination with the central supply and safety valve 19 by the whole of the mechanism represented by Figure 16.

The entirety of these mechanisms comprises, first of all, and made directly in the rotor shaft of each turbine opposite the oil pump mentioned above, an impeller, or pressure generator 8, or centrifugal oil pump 180 with radial blades, supplied with oil under pressure through piping 181 connected on to the piping 7, itself connected, as already explained, to the piping 6 into which the principal ejector 5 delivers and tending to deliver by its radial passages 182 oil under a higher pressure (corresponding to the square of the speed of rotation of the turbines) into piping 183 which runs to one of the relays of the group 9 of the safety relays.

This group which comprises as many relays as there are turbines, is constituted by a cover 184 inside which are arranged as many cylindrical cavities as there are relays, each cylinder containing a disengagement piston 185, comprising along its axis a conduit 186 provided with a

throttle 187, the said piston being subjected to the action of a spring 188 which bears against the upper cover of the casing 184.

There terminate at the said casing:

1st—the pipe 59 referred to above and which starts from the pipe 57 supplying the central valve 19.

2nd—an exhaust or escape pipe 189.

3rd—a rotative balancing pipe 190 which is connected on to the pipe 181 and which is consequently in connection with the pipe 7.

4th—the various pipes 183 coming from the different pumps, each ending in a plug 191 connected to the casing 184 and fitting in the lower enlarged part 185a of the corresponding piston 185, opposite a bore 187a, communicating with the throttle 187.

And finally 5th, the pipe 23, hereinbefore described, which runs to the central control station where there is arranged the third element of the safety system, that is to say, the control mechanism which if necessary can be substituted at will for the automatic action of the group of safety relays.

The control mechanism in question comprises a cylinder 26 at which terminates the pipe 23 and in this cylinder, a piston valve 193 provided with a groove 194 into the interior of which there penetrates a projection 195.

The said valve 193 is subjected to the action of a spring 196 and the rod 197 at the extremity of which it is arranged, is provided at its other extremity with a draw handle 198.

From the cylinder 26 and opposite the valve 193 there starts the exhaust pipe 24 described in connection with Fig. 1.

The inner walls of the cylinders of the different safety relays are provided with annular grooves 184a communicating with each other by means of ducts 184b so that when the pistons of the said relays are in their lower position, the pipe 59 is in communication with the pipe 23 without, however, communicating either with the pipe 189 or with the pipe 190.

It follows that as long as the members are in the position in which they are shown in Figure 16, the pipe 59 is closed since the orifice 200 of the pipe 23 is closed, and since there is no communication open between the pipe 59 and the pipe 189. But if owing to an excessive increase in the speed of one of the turbines, one of the pumps 8 commences to deliver oil into its pipe 183 under a pressure such that it causes the corresponding piston 185 to rise, which rise owing to the shape of the lower part of the piston, rapidly becomes a total one, as soon as it has commenced, the pipe 59 is immediately placed in communication with a discharge pipe 189 and the pressure applied under the control piston 48 of the closing portion of the central valve 19 disappearing, the valve closes instantly, thus cutting off the supply of all the turbines.

Similarly if, acting on the handle 198, the valve 193 is drawn from the right towards the left, so as to uncover and consequently open the orifice 200 and thus place the pipe 23 in communication with the escape pipe 24, the same phenomenon is produced and the central supply valve, supposing that it were open, is closed again.

This latter mechanism is useful in particular during the preparatory period previous to the starting of the locomotive, that is to say, for the period of heating.

Before everything, the driver commences by opening the passage between the pipe 23 and the

pipe 24, and to this end he draws to its full extent the valve 193 and causes it to slightly rotate, so that the groove 194 no longer being opposite the projection 195 it is held by the latter; it is only then that by acting on the cock 28 he starts the auxiliary pump 2.

When the pressure of the oil delivered by the latter attains the desired amount, the driver by acting on the handwheel 27 causes the full opening of all the admission valves for forward running and he then closes the valve 193, thus causing the opening of the auxiliary valve 34 of the central supply valve.

As has already been explained above, for the effective starting of the locomotive the driver completely closes all these individual groups of valves, thus causing the full opening of the central supply valve and it is only then that he opens afresh according to requirement, the individual groups of valves for forward running or backward running.

To briefly summarize the operation of the system described above, and assuming that the turbines are cold and the steam inlet control or safety valves are closed and pump 2 at rest, then to heat up the turbines prior to operation the operator draws out handle 198 of the starter and safety control 26 (Figs. 1 and 16) and turns it to lock it in open position. Pipe 23 is then connected through the interior of cylinder 194 with

the outlet pipe 24 leading to the reservoir 3. No oil under pressure is admitted to piston 53 of distributor 18 and the central steam valve 32 as well as its auxiliary valve 34 cannot open. Cock 28 is then operated to start the supplementary pump 2. Pump 2 supplies oil under pressure to ensure an adequate circulation of lubricant and feeds the pressure reducing valve 13 as well as the various control devices. The operator then manipulates handwheel 27 to open valves 123, 124 and 125 of the turbines. Cam 81 immediately opens valve 102 and oil under pressure enters through pipe 101a and flows beneath the valve 111. Further rotation of the handwheel 27 increases the pressure exerted by spring 113 on the valve 111 and increases the oil pressure in line 119a which communicates with the control relays 16 of the valves. Slide 148 descends and connects the channel 146 with outlet 157 and also connects inlet 156 with pipe 145. Pistons 142 and 143 of each relay 16 are lowered rotating lever 134 and opening inlet valves 123, 124 and 125 of each turbine. The operator then rotates handle 198 of control 26 and returns it to its normal position severing communication between pipes 23 and 24.

Oil under pressure in pipe 57, since it cannot escape through pipe 59, builds up sufficient back pressure to move the piston 53 of distributor 18 to the left (Fig. 2) permitting oil to pass beneath piston 48 and move it upwardly to open pilot valve 34. Steam in pipe 30 then passes into chamber 36 and through orifices 37 and valves 34 into pipe 31 and thence to the turbines. The small amount of steam passing valve 34 exerts no action upon the turbines other than exchange of heat. Valve 32 cannot open at this time as the pressure exerted thereon by the steam in chamber 36 is greater than that exerted by the oil on piston 38. When pilot valve 34 opens the pressure exerted on valve 11 of the control device 20 is increased and this increase effects a corresponding increase of pressure in pipe 14 and consequently in pipe 21 connected with the gauge 22 and the pointer of gauge 22 moves to the indicia representing "Heating up."

When the turbines have been heated the operator closes the steam inlet valves of the turbines by rotating handwheel 27 back to its initial position. The steam passing pilot valve 34 can no longer flow into the turbines and so sets up a counterpressure below the valves 32 and 34 in chamber 45 which soon balances the pressure exerted in chamber 36. The oil under pressure beneath piston 48 then raises piston 48 and opens valve 32. Opening of valve 32 increases the pressure on valve 71 and increases the pressure of the oil in pipe 74. This increased pressure is shown on gauge 22 when the pointer is opposite the indicia representing "Opening."

The system is now ready for starting the turbines. The operator rotates handwheel 27 to open steam inlet valves 123, 124 and 125 and the turbines are placed in operation. When the turbines reach a predetermined speed the pressure of the oil supplied by pumps 4 fed into trunk line 1 becomes greater than the pressure provided by auxiliary pump 2. Inlet cock 29 then automatically closes thereby stopping pump 2.

During normal operation the power developed by and the speed of the turbines are regulated as desired by handwheel 27 which controls the amount of opening of the steam inlet valves of the turbines.

To reverse the direction of rotation of the turbines the inlet valves are closed and the operator manipulates handwheel 27 in the opposite direction to open the reverse valves 126. Rotation of handwheel 27 opens valve 103 and forces valve 112 against its seat increasing the pressure beneath valve 112 and in pipe 120a to operate relays 17 and open the reverse valves 126.

If the speed of one or more of the turbines increases beyond the speed determined by the position of handwheel 27, oil under increased pressure is delivered by its pump 8 to its pipe 183 and forces the corresponding piston 185 of the safety relay to rise, thus short-circuiting pipe 59 through drainage pipe 189. This reduces the pressure of the oil beneath piston 48 and valves 32 and 34 close immediately shutting off the supply of steam to all the turbines. When the speed of the turbines has been reduced so that the pressure in pipe 183 allows piston 185 to resume its normal position the connection between pipe 159 and 189 is broken and the oil pressure builds up in pipe 57 and reopens valves 32 and 34. The operator then opens the inlet valves which he has meanwhile closed when he perceived that the pointer of gauge 22 indicated "Closed."

To stop the turbines handwheel 27 is rotated to its position for which all of the forward and reverse drive valves are closed. This automatically places the supplementary pump 2 in operation. Should the stop be one of long duration the operator closes cock 28 stopping pump 2 and valves 32 and 34 close as soon as the pressure of oil drops beneath piston 48.

At any time during operation the supply of steam to all of the turbines can be shut off instantaneously by drawing out handle 198. This places pipes 23 and 24 in communication and reduces the pressure in the cylinder 47 immediately closing valves 32 and 34.

I claim:

1. A hydraulic control and pressure lubrication system for a plurality of turbines which are subject to large variations in load and speed, comprising a high pressure oil line, means for maintaining therein a pressure which is variable but 75

- above a predetermined value comprising pump means driven by the turbines and subject to similar variations in speed and pressure-controlled auxiliary pump means subjected to the pressure in said line and operative when the pressure generated by said turbine pump means drops below said predetermined value, a secondary oil circulation system, means for supplying oil to said secondary system at a constant pressure less than said predetermined value comprising a pressure-reduction valve interposed between and connecting said system with said high pressure line, and pressure-responsive hydraulic control means for said turbines operated by the oil pressure in said secondary system.
2. The system defined in claim 1, in which said control means comprise a main steam supply control device for said turbines having a pilot valve and a main valve, and pressure-responsive hydraulic means connected to said secondary system for opening said pilot valve and main valve in succession to supply steam to said turbines first through said pilot valve for heating the turbines and thereafter through said main valve for operating the turbines.
3. The system defined in claim 1, in which said control means comprise a main steam supply control device for said turbines having a pilot valve and a main valve, pressure-responsive hydraulic means connected to said secondary system for opening said pilot valve and main valve in succession, and means operative on opening of said pilot valve to supply low pressure steam to the discharge side of said main valve for heating said turbines, said low pressure being insufficient in proportion to the main steam pressure for said main valve to be opened by said pressure-responsive means, whereby stopping the admission of heating steam to said turbines causes an increase of the steam pressure on the discharge side of said main valve and opening of the latter by said pressure-responsive means.
4. The system defined in claim 1 in which said control means comprise a main steam supply control device for said turbines having a pilot valve and a main valve, pressure-responsive hydraulic means connected to said secondary system for opening said pilot valve and main valve in succession to supply steam to said turbines first through said pilot valve for heating the turbines and thereafter through said main valve for operating the turbines, and a manually operable device for controlling the supply of oil to said pressure-responsive means.
5. The system defined in claim 1, in which said control means comprise a main steam supply valve for said turbines, pressure-responsive hydraulic means connected to said secondary system for opening said valve, an oil pressure release line for said pressure-responsive means, a plurality of pressure-responsive release means for said release line, and a plurality of oil pressure generators one driven by each turbine and one connected to each of said release means, whereby the pressure generated by excessive speed of any turbine releases the pressure on said hydraulic means and causes closing of said valve.
6. The system defined in claim 1, in which said control means comprise a main steam supply valve for said turbines, pressure-responsive hydraulic means connected to said secondary system for opening said valve, an oil pressure release line for said pressure-responsive means, a plurality of pressure-responsive release means for said release line, and a plurality of oil pressure gen-

erators one driven by each turbine and one connected to each of said release means, whereby the pressure generated by excessive speed of any turbine releases the pressure on said hydraulic means and causes closing of said valve, and a manually operable pressure-release means also connected to said release line.

7. The system defined in claim 1, in which said control means comprise forward and reverse running admission valves for each turbine, hydraulic servo-motors for operating said valves, and means for supplying oil under controllable pressure from said secondary system to the group of forward running servo-motors in common and to the group of reverse running servo-motors in common and comprising separate valve means for each group of servo-motors, said valve means being connected to said secondary system and being independently adjustable to regulate the pressure of the oil delivered to said groups of servo-motors.

8. The system defined in claim 1 in which said control means comprise forward and reverse running admission valves for each turbine, hydraulic servo-motors for operating said valves, and means for supplying oil under controllable pressure to the group of forward running servo-motors in common and to the group of reverse running servo-motors in common and comprising a valve chest connected to said secondary system, separate valve means for controlling the delivery of oil from said chest to said groups of servo-motors, a control member for operating one of said valve means in one direction of movement and the other valve means in the opposite direction of movement, and means regulating the pressure of the oil delivered to said groups of servo-motors in proportion to the extent of movement of said control member.

9. The system defined in claim 1, in which said control means comprise forward and reverse running admission valves for each turbine, hydraulic servo-motors for operating said valves, and means for supplying oil under controllable pressure to the group of forward running servo-motors in common and to the group of reverse running servo-motors in common and comprising a valve chest connected to said secondary system, a stop valve and a pressure-regulating valve for controlling the delivery of oil from said chest to each group of servo-motors, a control member for operating said valves for one group of servo-motors in one direction of movement and the valves for the other group of servo-motors in the opposite direction of movement, and operating means connecting said member and valves for opening the stop valve and progressively operating the pressure-regulating valve as said member moves away from normal position.

10. In a control system for a plurality of steam turbines including an oil reservoir, a primary circulating system for circulating oil under pressure, a secondary system for circulating oil under reduced and constant pressure, pressure reducing means connecting said primary circulating system and said secondary system, a pump connected to said oil reservoir to supply oil under pressure to said primary system during starting and slow running of the turbines, pumps driven by the turbine shafts supplying oil to said primary system during normal operation of the turbines, im-

5 pellers driven by the turbine shafts, safety relays for each of the turbines, means connecting said impellers and said safety relays whereby said safety relays are actuated by the oil delivered by said impellers.

11. In a control system for a plurality of steam turbines including an oil reservoir, a circulating system for circulating oil under pressure, a pump in the oil reservoir to supply oil under pressure to said system during starting and slow running of the turbines, pumps driven by the turbine shafts supplying oil to said system during normal running of the turbines, a secondary circulating system, a pressure reduction valve, means connecting said pressure-reduction valve to said circulating system and to said secondary circulating system whereby oil under reduced but constant pressure is delivered to said secondary system, a main steam supply valve for said turbines, an auxiliary steam supply valve slidable within said main steam supply valve, pressure responsive means to operate said auxiliary and said main steam supply valves, means connecting said pressure responsive means to said secondary circulating system whereby oil under low and constant pressure is supplied to said pressure responsive means to actuate said valve.

12. In a control system for a plurality of steam turbines including an oil reservoir, a circulating system for circulating oil under pressure, a pump in the oil reservoir to supply oil under pressure to said system during starting and slow running of the turbines, pumps driven by the turbine shafts supplying oil to said system during normal running of the turbines, a secondary circulating system, a pressure-reduction valve, means connecting said pressure-reduction valve to said circulating system and to said secondary circulating system whereby oil under reduced but constant pressure is delivered to said secondary system, a valve control chest connected in said secondary circulating system, a control rod rotatably mounted in said control chest, pistons mounted in said control chest and adjustable by said control rod, a series of servo-motor relays for governing said turbines, means connecting said servo-motor relays and said valve control chest whereby the speed and direction of said turbines are controlled by the positions of said pistons.

13. In a control system for a plurality of steam turbines including an oil reservoir, a circulating system for circulating oil under pressure, a secondary circulating system for circulating oil under reduced pressure, pressure reducing means connecting said circulating system and said secondary circulating system, a primary pump connected to said oil reservoir to supply oil under pressure to said circulating system during starting and slow running of the turbines, pumps driven by the turbine shafts supplying oil to said circulating system during normal operation of the turbines, impellers driven by the turbine shafts, safety relays for each of the turbines, means connecting said impellers and said safety relays, a main steam valve for said turbines, pressure responsive means for controlling said main steam valve, means connecting said safety relays with said pressure responsive means whereby said main steam valve may be closed by said safety relays.

FRANÇOIS MARIE ANDRÉ
ATHANASE WALCKENAER.
